UNITED STATES PATENT OFFICE.

WALTER R. SCHINDLER, OF LONG BEACH, CALIFORNIA.

PLANT-PROTECTING CAP.

1,340,631.

Specification of Letters Patent. Patented May 18, 1920.

Application filed October 8, 1919. Serial No. 329,309.

To all whom it may concern:

Be it known that I, WALTER R. SCHINDLER, a citizen of the United States, residing at Long Beach, in the county of Los Angeles, State of California, have invented a new and useful Plant-Protecting Cap, of which the following is a specification.

My invention relates to devices for covering plants and has more particular relation to plant protecting caps adapted to be placed over young plants to protect them from the sun or frost or from injurious insects.

The object of the invention is to provide a protecting cap which is preferably formed of semi-opaque material such as will exclude the sun's rays and at the same time admit sufficient light to promote the growth of the plant.

A further object is to provide a cap of circumferential form having anchor means for anchoring the cap in the ground and contoured to provide a substantial strong structure presenting a minimum wind resisting surface so that it will not be easily displaced by wind currents.

Various other objects and advantages will be apparent from the following detailed description of the preferred form of embodiment of the invention as illustrated in the accompanying drawings forming a part of this disclosure, and in which—

Figure 1 is a plan view of the circular blank which is pressed into shape to form my improved cap.

Fig. 2 is a side elevation of the cap.

Fig. 3 is an enlarged plan section on line x^3-x^3 of Fig. 2.

Fig. 4 is a transverse vertical section through the cap.

In the drawings, 1 designates the circular blank, preferably of waxed or oil treated paper, which is pressed to form the protecting plant cover or cap. The cap is formed with side sections 2-3 and top section 4, the side section 2 extending a relatively short distance upwardly to a line of fold 5 defining the point of junction of the section 2 with the adjacent section 3, the walls of the section 2 converging inwardly at a slight angle. The side section 3 extends upwardly a relatively greater distance to a second line of fold 6 defining the point of junction of said section 3 with the top section 4, the walls of the section 3 converging inwardly at a relatively greater

angle than do the walls of the section 2. The top section 4 is of relatively flat cone formation and the peripheral base edge of the section 2 has a flange 7 turned outwardly to provide an anchor means for anchoring the cap in position, said flange being below the surface of the ground when the cap is in position of use (see Fig. 4).

In the pressing into shape of the circular blank, plaits or folds 8 will be created at various points around the sides of the cap. These folds are not located at definite circumferential positions nor are they of any definite form or size, their positions and forms depending upon the inherent peculiarities of each blank and the pressing action of the dies used in the manufacture of the cap.

The side sections 2-3 are each of frustated-cone formation joined in superposed relation and surmounted by a relatively flat cone-shaped top section, the cone section 2 having a flanged peripheral base and each section converging inwardly at relatively increased angles.

The flat cone-shaped top section and the slanting side sections provide a substantial and strong structure which is further strengthened by the folds 8, and the entire cap being of stream-line contour presents a minimum wind resisting surface to the action of air currents such as would have a tendency to displace the cap.

In use the cap is placed over a plant with the anchor flange below the surface of the ground, as indicated in dotted lines in Fig. 4, and being constructed of semi-opaque material excludes the sun's rays while at the same time admits sufficient light to promote the growth of the plant. The cap will also effectively protect the plant against injury by frost or those classes of injurious insects which live near or above the surface of the ground.

I claim:

1. A plant protecting seamless cap comprising a plurality of superposed frustated cone-shaped side-wall sections surrounded by a relatively flat cone-shaped top wall section, the peripheral base edge of the lower wall section being flanged outwardly.

2. A plant protecting seamless cap comprising a plurality of superposed frustated cone-shaped side wall sections surrounded by a relatively flat cone-shaped top wall section, the walls having plaits ex-

tending upwardly from the peripheral base edge of the lower section.

3. A plant protecting seamless cap comprising three superposed sections, the base section having inwardly converging walls, the intermediate section having inwardly converging walls angled to a greater degree than the walls of the base section and the top section being of relatively flat cone shape.

4. A plant protecting seamless cap comprising three superposed sections, the base section having inwardly converging walls, and a peripheral base flange, the intermediate section having inwardly converging walls angled to a greater degree than the walls of the base section and the top section being of relatively flat cone shape.

5. A plant protecting seamless cap formed from a circular blank pressed into shape to provide side walls converging inwardly

to a line of fold, then converging inwardly at a relatively greater angle to a second line of fold and terminating in a point above said second line of fold to form a 25 cone-shaped top wall.

6. A plant protecting seamless cap having a peripheral base flange and formed from a circular blank pressed into shape to provide side walls converging inwardly to a 30 line of fold, then converging inwardly at a relatively greater angle to a second line of fold and terminating in a point above said second line of fold to form a cone-shaped top wall.

Signed at Los Angeles, California, this 35
1st day of October 1919.

WALTER R. SCHINDLER.
